UNITED STATES PATENT OFFICE.

FREDERICK MAX PORITZ, OF NEW YORK, N. Y., ASSIGNOR TO ARTISTIC BRASS & BRONZE WKS. INC., A CORPORATION OF NEW YORK.

DESIGN FOR A COLUMN FOR LIGHTING FIXTURES OR SIMILAR ARTICLES.

Application filed July 20, 1925. Serial No. 14,152. Term of patent 3½ years.

To all whom it may concern:

Be it known that I, FREDERICK MAX PORITZ, a citizen of Germany, residing at New York, in the county of New York and State of New York, have invented a new, original, and ornamental Design for Columns for Lighting Fixtures or Similar Articles, of which the following is a specification, reference being had to the accompanying drawing, forming part thereof.

The figure is a plan view of a column for lighting fixtures, or similar articles, showing my new design.

I claim:

The ornamental design for a column for lighting fixtures or similar articles, as shown.

FREDERICK MAX PORITZ.
